Primary Examiner — Philip S Hyder(74) *Attorney, Agent, or Firm* — Downs Rachlin Martin PLLC(57) **CLAIM**

The ornamental design for a can opener drive gear, as shown and described.

DESCRIPTION

FIG. 1 is a perspective view of a can opener drive gear showing my new design;

FIG. 2 is a front view thereof;

FIG. 3 is a rear view thereof;

FIG. 4 is a side view thereof;

FIG. 5 is a second side view thereof;

FIG. 6 is a top view thereof;

FIG. 7 is a bottom view thereof; and,

FIG. 8 is a cross sectional view taken along line 8-8 of FIG. 2.

The dash-dash broken lines in the Figures are for the purpose of illustrating unclaimed portions of the can opener drive gear and form no part of the claimed design.

The dot-dash broken lines are boundary lines and represent boundaries of the claimed design and do not form part of the claimed design. The shade lines in the Figures show contour and not surface ornamentation.
